FOLDING IRONING TABLE

Kemuel B. Olander, Minneapolis, Minn.

Application June 20, 1934, Serial No. 731,481
Renewed January 10, 1936

6 Claims. (Cl. 88—117)

My invention relates to folding ironing tables, and an object is to provide a folding device of this character which is of extremely simple and strong construction and which can be quickly unfolded from a folded condition and set up in such manner that the ironing board will be firmly supported in horizontal position. Another object is to provide an ironing table having supporting legs whose lower ends are automatically spread when the table is opened in order to provide a broader base for supporting the board and which are brought closer together when the table is folded whereby the legs are caused to lie within the margins of the board.

The full objects and advantages of my invention will appear in connection with the detailed description thereof and the novel features embodied in my inventive idea will be particularly pointed out in the claims.

In the accompanying drawings which illustrate a practical embodiment of my invention,—

Fig. 1 is a side elevational view of the ironing table in set-up or unfolded condition. Fig. 2 is a front elevational view. Fig. 3 is an enlarged fragmentary view on the line 3—3 of Fig. 1. Fig. 4 is an enlarged fragmentary view on the line 4—4 of Fig. 1. Fig. 5 is a fragmentary view in longitudinal section on the line 5—5 of Figs 3 and 4. Fig. 6 is a bottom plan view of the table in unfolded position. Fig. 7 is a bottom plan view of the table in folded position. Fig. 8 is an enlarged fragmentary view on the line 8—8 of Fig. 2. Fig. 9 is an enlarged fragmentary view on the line 9—9 of Fig. 2.

As shown in the drawings, I provide an ironing board 10 to the underside of which near its rear end is secured a cleat or transverse strip 12. As best shown in Fig. 2, this cleat is beveled or thinned down from its middle toward both ends. As will be apparent from Figs. 6, 7 and 8 each beveled portion of the cleat 12 carries similar bearing members 14 and 16 secured thereto by rivets 18 which also serve to secure the cleat to the board 10. Each set of bearing members 14 and 16 rotatably holds rods 20 respectively. These rods at their outer ends as shown in Figs. 2 and 7 are bent twice at right angles to form portions 22 which are riveted to the upper ends of rear legs 24. The rods 20 at their inner ends are bent at an acute angle to form brace members 26 which at their lower ends are bent to form portions 28 which are substantially parallel with the body portions of the rods 20. The portions 28 not only pass through intermediate points of the legs 24, but also through the lower ends of brace bars 30

and through the upper ends of tension rods 32, the rods 32 being inside of the legs 24 and the bars 30 being inside of the rods 32. The portions 28 therefore constitute pivot members on which the lower ends of the brace bars 30 and the upper ends of the tension rods 32 are adapted to turn for the folding and unfolding operations.

The tension rods 32 are as shown in the form of a bifurcated or V shaped member the apex or lower end of which is slightly flattened and pivotally attached to the lower end of a third leg 34 whose upper end is pivotally attached by a pivot 35 to a bifurcated bracket 36, the rear portions of the bifurcations being connected by an inclined member 38 with which the beveled end of the leg 34 engages as shown in Fig. 5 when the table is in unfolded condition. The bracket 36 is secured to the underside of the board 10 substantially centrally thereof by rivets 40. The upper ends of the brace bars 30 are brought rather close together and joined by a slide 42 to which they are pivotally attached by pivots 43. As best shown in Fig. 3, the slide 42 has a flat portion adapted to slide in a slideway 44 secured by screws 46 to the underside of the forward portion of the board 10. The slide 42 carries a leaf spring 48 best shown in Figs. 3 and 5 which is provided with a projection 50 adapted to snap into a hole 52 in the rear portion of the slideway 44 when the table is placed in unfolded position. The brace bars 30 are connected by a flexible element 54 which when the table is in folded condition comes underneath the third leg 34 as shown in Fig. 7.

The operation and advantages of my invention will be readily understood in connection with the foregoing description and the accompanying drawings. When it is desired to set up the table from its folded condition shown in Fig. 7, the leg 34 is grasped and turned on its pivot which is carried by the bracket 36. The leg 34 engages the flexible element 54 to overcome the dead center of the brace bars 30 so that the lower ends of these bars turn on the pivot members 28. The upper ends of the tension rods 32 will also turn on these pivots. During this movement, the slide 42 is brought rearwardly in the slideway 44 and when the table reaches its completely unfolded position, the projection 50 snaps into the hole 52 so that the movable members are held rigidly in position. At the same time, the lower ends of the two legs 24 are spread from the position shown in Fig. 7 into that shown in Figs. 2 and 6. This spreading action is caused by the inclined position of the rods 20 relatively to the plane of the board 10. Since the legs 24 are secured to the

rods 28 at right angles thereto, it is obvious that they must swing in planes inclined to the board 10 with the result that the lower ends of the legs are gradually spread as the device is opened up 5 from the position of Fig. 7 into that shown in Figs. 2 and 6. When it is desired to fold the table, the projection 50 is released from the hole 52 and the leg 34 pushed in reverse direction. By referring to Fig. 7, it will be understood that when the 10 table is in the folded condition there shown, the pivots 28 and 43 at the two ends respectively of the brace bars 30 are at substantially the same distance below the board 10 and therefore the brace bars 30 are in dead center position. When 15 the leg 34 is moved away from the board 10 for the unfolding operation, the leg engages the flexible element 54, thereby causing the ends of the brace bars 30 which are provided with the pivots 28 to swing away from the board.

20 I claim:

1. A folding ironing table comprising a board, a pair of rods rotatably mounted on the underside of said board near one end thereof, said rods respectively being inclined downwardly from positions adjacent the side edges of said board toward a position beneath the median line of the board, a pair of legs secured at their upper ends to the outer ends respectively of said rods at right angles to the latter, the inner ends of 25 said rods being bent downwardly and outwardly and attached to intermediate points of said legs to form pivots, a third leg pivotally attached to the underside of said board, and connections between said leg and said pivots which cause all of 30 the legs to fold and unfold in unison.

2. A folding ironing table comprising a board, a cleat beveled from its middle toward its ends secured transversely to the underside of said board near one end thereof, bearings secured to 40 the beveled surfaces of said cleat, rods rotatably mounted in said bearings parallel to said beveled surfaces, a pair of legs secured at their upper ends to the outer ends respectively of said rods at right angles to the latter, the inner ends of 45 said rods being bent downwardly and outwardly and attached to intermediate points of said legs to form pivots, a third leg pivotally attached to the underside of said board, and connections between said leg and said pivots which cause all of 50 the legs to fold and unfold in unison.

3. A folding ironing table comprising a board, bearings mounted on the underside of said board near one end thereof and disposed on opposite sides of the median line of the board, rods rotatably mounted in said bearings respectively and inclined upwardly toward the respective side edges of said board, a pair of legs secured at

their upper ends to the outer ends respectively of said rods at right angles to the latter, the inner ends of said rods being bent downwardly and outwardly and attached to intermediate points of said legs, a third leg pivotally attached to the underside of said board, and connections between said leg and said legs which cause all of the legs to fold and unfold in unison. 5

4. A folding ironing table comprising a board, a pair of legs pivotally attached at their upper ends to the underside of said board near one end thereof, a third leg pivotally attached to the underside of said board, mechanical connections between said third leg and said pair of legs for causing them to fold and unfold in unison, brace 10 bars pivotally attached at one end to said pair of legs respectively, means slidably connecting the other end of said bars to said board, and a flexible element connecting said brace bars in 15 such position as to be engaged by said third leg 20 to overcome the dead center of said brace bars when the unfolding operation is started.

5. A folding ironing table comprising a board, a pair of legs pivotally attached at their upper ends to the underside of said board near one end thereof by individual pivots set at inclined angles with the plane of said board respectively whereby each of said pivots is inclined away from the surface of said board toward the medial line of the latter, a member held in slidable engagement 30 with said board, a pair of brace bars attached at their upper ends by pivots axially parallel with said leg pivots respectively to said slidable members, and having their lower ends pivotally attached to said pair of legs at intermediate points 35 thereon, a third leg pivotally attached to the underside of said board, and mechanical connections between said third leg and said pair of legs for causing all of said legs to fold and unfold 40 in unison.

6. A folding ironing table comprising a board, a pair of legs pivotally attached at their upper ends to the underside of said board, a third leg pivotally attached to the underside of said board, mechanical connections between said third leg and said pair of legs for causing them to fold and unfold in unison, brace bars pivotally attached at one end to said pair of legs respectively, means slidably connecting the other end of said bars to said board, and means associated with 45 said brace bars and said third leg whereby said brace bars are forced outwardly from their folded position by movement of said third leg outwardly from its folded position when the unfolding operation is started. 50

KEMUEL B. OLANDER.
